UNITED STATES PATENT OFFICE

WALTER VOORTMANN, OF DORTMUND, GERMANY

SAFETY DEVICE FOR BLASTING CHARGES EMPLOYED IN MINING AND SIMILAR WORK

Application filed January 16, 1931, Serial No. 509,247, and in Germany March 5, 1930.

This invention relates to a protective device for the blasting charges that are usual in mining and similar operations. It is known to mount upon a blasting charge located in a bore hole, before tamping or stemming it, a plug that receives a pulling member, for the purpose of enabling the blasting cap to be pulled out again in the event of failure of the explosion, after the tamping 10 that closes the bore hole, consisting of moist clay or the like, has been removed.

The object of the present invention is to provide a protective device for the blasting charges that are usual in mining and similar 15 operations, characterized by the feature that the plug, made of an incombustible material, impregnated wood for example, or an incombustible artificial material, is provided with two longitudinal bores, for the ignition wires 20 and for the pulling member respectively, and has on the outside axially arranged and preferably dovetail-shaped notches for the reception of supporting members for a partial charge.

According to a further feature of the invention the bore in the plug for the pulling member is located centrally, and has at the inner end a conical expansion.

According to another feature of the invention the pulling member consists of an incombustible string or wire, which is held in the bore of the plug by a knot and preferably has a coloured marking.

According to yet a further feature of the invention the margins of the recesses in the plug for the supporting members are somewhat convergent towards one end, and the supporting members, which consist of incombustible material, such as presspahn for example, are provided with transverse holes at their ends.

By locating the pulling member exactly in alignment with the axis of the bore hole for the blasting charge, and firmly connecting a partial charge with the plug by means of the supporting members, a reliable guidance is established in the bore hole when inserting and withdrawing the plug. In consequence 50 of the coloured marking of the string it can

at any time be ascertained how deep the plug is in the hole.

The invention is illustrated by way of example in the accompanying drawing, in which

Figure 1 shows a back view of the plug according to the invention.

Figure 2 a side view of the plug.

Figure 3 a side view of a plug with supporting members inserted and a partial charge fitted in,

Figure 4 a side view of a supporting member, and

Figure 5 a blasting charge inserted in the bore hole, on a smaller scale.

A cylindrical plug 1, illustrated in the drawing, preferably consists of an incombustible material, for instance impregnated wood or an artificial material. The plug has in an axial direction a central cylindrical bore 2 for the reception of a pulling member, not shown, an incombustible string or wire α for example. The bore 2 is conically flared towards the inner end of the plug, and in this conical widening 3 is placed a knot on the pulling member, which prevents the string from being dragged out of the plug. Parallel to the bore 2 is provided a second bore 4, through which ignition wires c , c' for the blasting cap d . In the cylindrical surface of the plug are cut dovetail-shaped grooves 5 and 6 parallel to the axis, which taper towards the inside of the plug, as shown in Figure 2. Into the dovetail-shaped grooves are inserted from the outside supporting members 7 and 8, which likewise consist of an incombustible material, such as presspahn. The shape of these supporting members is externally adapted to the periphery of the plug. The supporting members 7 and 8 are long bars, which are provided in the neighbourhood of their ends with transverse holes 9 and 10 respectively. Owing to the fact that the grooves 5 and 6 taper inwards to some extent, the supporting members are firmly connected with the plug.

The supporting members 7 and 8 serve to hold a partial charge e inserted between them. The ignition wires are passed through the bores 4, and the inner end of the

partial charge is held by a string *f* of incombustible material, which passes through the holes 9 and 10.

If no partial charge is desired between the bars they may be omitted, and the ignition wires may be passed through the laterally provided grooves. The plug may also be directly connected with the fuse, and the ignition wires are then so strong that they serve 10 as a pulling member.

When inserting the partial charge connected with the plug, the whole is introduced so far into the bore hole that the inner ends of the supporting members come into contact 15 with the preceding partial charge, as shown in Figure 5. The string, not shown, projecting from the outer end of the plug, and preferably having a colored marking, every 25 centimetres for instance, indicates how deep 20 the plug is in the bore hole.

The free end of the bore hole is closed in the usual manner, after the insertion of the plug, by the so-called tamping or stemming *g* or moist clay or the like. The string or the 25 pulling member then projects out, as do also the ignition wires.

If a miss-fire occurs, the tamping is blown 30 out of the bore hole by compressed air by means of a blast pipe having an internal diameter of about 10 millimetres, and by exerting a pull on the string or wire *a* or on the ignition wires, the plug can be drawn out, together with the partial charge (if any) connected with it. In Figure 5 three partial 35 charges are shown, inserted in one bore hole.

What I claim is:—

1. A safety device for blasting charges employed in mining and similar operations, consisting in the combination of a cylindrical 40 plug of incombustible material provided with a central passage, and a pulling member anchored axially of the passage in the plug, the pulling member being marked at definite distances.

45 2. A safety device for blasting charges employed in mining and similar operations, consisting in the combination of a cylindrical plug of incombustible material provided with a central passage, and a pulling member 50 anchored axially of the passage in the plug, ignition wires, the plug being formed with a second passage, parallel to the said central passage, for the ignition wires.

55 3. A safety device for blasting charges employed in mining and similar operations, consisting in the combination of a cylindrical plug of incombustible material and a pulling member attached centrally to the plug, 60 ignition wires, the plug being formed with a central passage for the pulling member, and with a second passage, parallel to the said central passage, for the ignition wires, and with dovetail-shaped slots in its cylindrical 65 surface, supporting members engaging in the

said slots, and a partial charge held between the supporting members.

4. A safety device for blasting charges employed in mining and similar operations, consisting in the combination of a cylindrical 70 plug of incombustible material, supporting members connected with the plug, a string holding the supporting members together, a partial charge held by the supporting members, and a pulling member attached centrally to the plug. 75

5. A safety device for blasting charges employed in mining and similar operations, consisting in the combination of a cylindrical 80 plug of incombustible material, supporting members connected with the plug, a string holding the supporting members together, a partial charge held by the supporting members, and a pulling member attached centrally to the plug, the pulling member 85 being marked at definite distances.

6. A safety device for blasting charges employed in mining and similar operations, consisting in the combination of a cylindrical 90 plug of incombustible material, and a pulling member attached centrally to the plug, the plug being formed with a central passage for the pulling member, supporting members connected with the plug, a string holding the supporting members together, a partial 95 charge held by the supporting members, a blasting cap, and ignition wires for the electrical ignition of the blasting cap.

In testimony whereof I have signed my name to this specification. 100

WALTER VOORTMANN.
